UNITED STATES PATENT OFFICE.

CARL E. L. LIPMAN, OF BELOIT, WISCONSIN.

AIR-MOTOR.

1,115,470.

Specification of Letters Patent.

Patented Oct. 27, 1914.

Application filed July 5, 1912. Serial No. 707,898.

To all whom it may concern:

Be it known that I, CARL E. L. LIPMAN, a citizen of the United States, residing at Beloit, in the county of Rock and the State 5 of Wisconsin, have invented certain new and useful Improvements in Air-Motors, of which the following is a specification.

The object of this invention is to construct a rotary valve for a multiple cylinder 10 air motor, comprising a solid shaft through which inlet and exhaust ports are formed.

In the accompanying drawings: Figure 1 is a longitudinal vertical section. Fig. 2 is a section on the line *a a* of Fig. 1. Fig. 3 is 15 a section on the line *b b* of Fig. 2. Fig. 4 is a section on the line *c c* of Fig. 1. Figs. 5, 7 and 9 show the positions of the intake port for the cylinder 2, on the line *d d* of Fig. 1. Figs. 6, 8 and 10 show the positions of the 20 exhaust port for the cylinder 2 on the line *e e* of Fig. 1. Fig. 11 is a diagram illustrating the portion of a revolution of the valve, the intake and exhaust ports are open, and the portion of a revolution in which 25 both ports are closed.

The motor shown in the drawings comprises the base 1 supporting the cylinders 2, 3 and 4. A crank shaft 5 is supported by the base and to it are connected the three 30 pistons 6, 7 and 8 for the cylinders 2, 3 and 4. A spur pinion 9 is connected to the crank shaft 5. The upper ends of the cylinders are formed with an outwardly extending flange 10. To the shaft 5 may be connected a gear or other means of transmitting power. Over the open upper ends of 35 the cylinders is located a valve casing 11 provided with a flange 12 by which it is connected with the flange 10 by the screws 13. This casing has a longitudinal cylindrical bore 14 within which is located the rotary valve 15. A cap 16 has a screw 40 thread connection with the one end of the valve casing and covers one end of the bore 45 14 and prevents the lengthwise movement of the rotary valve. A gear casing 17 is supported at its lower end by the crank shaft casing 1 and at its upper end by the valve casing 11. A cover 18 to the gear casing is 50 connected by the screws 19. A spur gear 20 is connected to the rotary valve 15, and intermediate spur gears 21 and 22 are supported by the casing 17 and cover 18 and mesh with the spur pinion 9 and spur gear 55 20, thereby forming a driving connection be-

tween the crank-shaft 5 and the rotary valve 15. The relative speed of the crank-shaft and rotary valve is two revolutions of the crank-shaft to one of the rotary valve. The upper portion of the valve casing is formed with two cavities or compartments 23 and 24. The compartment 23 has an intake port 25 and the compartment 24 has an exhaust opening 26.

As there are three cylinders, there are 60 three intake ports 27, 28 and 29 and three exhaust ports 30, 31 and 32 for the cylinders 2, 3 and 4 respectively. These ports extend vertically through the lower and upper walls of the central bore 14 in the valve 65 casing 11.

Through the rotary valve are formed three intake ports 33, 34 and 35 and three exhaust ports 36, 37 and 38 for the cylinders 2, 3 and 4 respectively. These ports 70 are arranged longitudinally of the rotary valve so that each cylinder is provided with an intake and an exhaust port. By fitting the rotary valve casing with a rotary valve 75 all of the parts in it can be machined independently of the cylinders and crank-shaft casing, and by forming the intake and exhaust ports of the casing in vertical alignment and the ports in the rotary valve radially therethrough, the intake of the air 80 and exhaust from the cylinders have a direct passage.

Figs. 5, 7 and 9 show the positions of the intake port 33, and Figs. 6, 8 and 10 show the positions of the exhaust port 36 during 85 one reciprocation of the piston 6.

Fig. 11 shows that the air is admitted during 128°, the exhaust is open 220°, and both intake and exhaust are closed during 6° between the intake and exhaust and between 95 the exhaust and intake.

I claim as my invention:

In a motor, the combination of a series of power cylinders arranged in alignment, a valve casing extending over the upper ends 100 of said aligned cylinders, communication being established between said casing and each of said cylinders through an intake and exhaust port in the top of each cylinder, said ports being arranged throughout the length 105 of the casing so that the inlet ports of adjacent cylinders are disposed in proximate relation and the exhaust ports of adjacent cylinders are also disposed in proximate relation, each pair of inlet ports alternating 110

in position with a pair of exhaust ports, a partition dividing said valve casing into an inlet chamber including all of said inlet ports and an exhaust chamber including all 5 of said exhaust ports, and a valve rotatably mounted in said casing for opening and closing said ports in predetermined relation.

In testimony whereof I have hereunto set my hand in presence of two subscribing witnesses.

CARL E. L. LIPMAN.
